WELDING GLOVE

Robert Bakke, Minneapolis, Minn.

Application May 23, 1946, Serial No. 671,798

4 Claims. (Cl. 2—161)

1

This invention relates to new and useful improvements in welders' gloves of the general type disclosed in my Patent No. 2,394,136, granted February 5, 1946.

The novel welding glove herein disclosed was developed after considerable experimental work in an attempt to provide a welder's glove which will present the utmost in practicability and comfort, and which may readily be manufactured in quantity production at low cost.

A further and more specific object of the invention is to provide a welder's glove comprising the usual back, palm, and finger portions secured together at the sides of the glove by suitable seams, and an elongated flexible strip of material such as leather being interposed between the back and palm portions of the glove and secured in position therein by said seams, said strips extending to the tips of the fore and fourth fingers, and also extending laterally from the sides of the glove, and a suitable fireproof shield overlying the back of the glove and having its opposed edges secured to the projecting portions of said leather strips, whereby the shield is secured to the glove along the sides thereof only, thereby to permit maximum freedom of movement of the intermediate fingers.

A further object is to provide a welder's glove comprising a flexible cuff or gauntlet portion and having a relatively nonflexible fireproof shield adapted to be fitted over the wrist or gauntlet portion of the glove to protect the latter against damage from sparks and bits of molten metal when the glove is in use.

A further object is to provide a highly efficient and practical welder's glove which is extremely simple in construction and which is so constructed that the fireproof back and cuff shields thereof do not interfere with the use of the operator's hand during a welding operation, the rear portion of the back shield being unattached to the gauntlet shield whereby the wrist movement of the user's hand is not impaired, which is highly desirable in a glove of this general character.

Other objects of the invention reside in the novel and inexpensive construction of the glove, whereby it may be manufactured in quantity production at extremely low cost; in the provision of the leather strips in the seams at the sides of the gloves; whereby the operation of securing the fireproof shield to the back of the glove is greatly facilitated; in the provision of a welding glove comprising a fireproof back shield and a fireproof gauntlet portion, the latter being in the form of a shield which is de-

tachably supported on the gauntlet portion of the glove in such manner that it may be readily detached therefrom when it is desired to use the glove without the gauntlet shield.

5 Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a perspective view of a welder's glove embodying my invention;

Figure 2 is a back view of the glove showing the simple manner of securing the fireproof shield to the back of the glove;

Figure 3 is a front view of the glove showing the cuff portion thereof collapsed to receive the fireproof cuff shield;

Figure 4 is a back view of the glove showing the fireproof shield attached to one side thereof only;

Figure 5 is an enlarged detail sectional view on the line 5—5 of Figure 4;

Figure 6 is a cross-section view on the line 6—6 of Figure 2; and

Figure 7 is a detail sectional view of a glove wherein a leather strip is embodied in the fore finger side of the glove only.

35 In the selected embodiment of the invention herein disclosed, there is illustrated in Figures 1 to 4, inclusive, a welder's glove comprising the usual back portion 2, palm portion 3, and finger portions 4, 5, 6, and 7, and a wrist portion 8.

40 The back and palm portions 2 and 3, respectively, and also the finger portions, are preferably constructed of a suitable leather which may have a high degree of flexibility and is highly resistant to wear. The gauntlet portion 8 of the glove is

45 also preferably of leather, although not necessarily so, and is stitched to the back and palm portions of the glove by a suitable seam 9 which may extend around the circumference of the glove, as shown in Figures 3 and 4. The back and palm portions of the glove are secured together by side seams 11 and 12, which are shown extending from the seam 9 to the tips of the fore finger and fourth finger, respectively, as best shown in Figure 4.

50 It is customary in welding gloves to provide a

fireproof shield at the back of the glove to protect the glove against sparks and bits of molten metal when the glove is in use, as shown, for example, in my aforementioned patent.

An important feature of the present invention resides in the novel manner in which I secure the fireproof shield to the back of the glove, whereby the construction of the glove prior to securing the shield in position thereon is not at all complicated, and also whereby the subsequent operation of securing the shield to the glove is greatly simplified.

To secure the fireproof shield to the back of the glove, as herein disclosed, a strip of flexible material such as leather, indicated by the numeral 13 in Figures 1, 2, and 4, is embodied in the side seam 11 of the glove, and a similar strip of leather 14 may be embodied in the side seam 12 at the opposite side of the glove, as best illustrated in Figures 4 and 6.

The fireproof shield, generally designated by the numeral 16, is preferably shaped as shown in Figure 4, and in the preferred construction of the glove one side edge thereof is secured to the leather strip 14 by such means as rivets 17. If desired, the leather strip 14 may also be bonded to the marginal edge of the shield 16 by a suitable adhesive, as will be understood. The shield may readily be secured to the leather strip 14 when in outwardly stretched position, as shown in Figure 4, wherein it will be noted the operation of securing the shield 16 to the outer side of the glove is greatly facilitated.

To complete the formation of the glove, the shield is folded over onto the back of the glove, as shown in Figure 2, and the leather strip 13 at the thumb side of the glove is then folded over the marginal edge of the opposite side of the shield 16 and adhered thereto by a suitable adhesive, as will be understood by reference to Figures 2 and 6. If necessary, suitable rivets 18 and 19 may be provided at the ends of the leather strip 13 to prevent the ends of the leather strip from becoming loose from the shield 16.

After the shield 16 has been suitably secured to the leather strips 13 and 14, as clearly illustrated in Figure 2, the offset portion 21 of the back shield 16, best shown in Figure 4, is secured to the outer wall portion of the thumb by suitable rivets 22, shown in Figures 1 and 2. A similar rivet 23 may be provided at the tip of the third finger 6 of the glove, as shown in Figure 2, although in some instances this rivet may be omitted.

From the foregoing, it will be noted that the operation of securing the back shield 16 to the glove is an extremely simple and inexpensive one. The insertion of the leather strips 13 and 14 in the seams 11 and 12, respectively, does not add to the cost of manufacturing the glove, and when embodied in the glove, as shown in Figure 4, the shield 16 may readily and expeditiously be secured in position over the back of the glove with a minimum of labor.

Another important feature of the invention resides in the provision of a wrist-protecting shield 24 adapted to be removably fitted over the usual gauntlet 8 of the glove, as will readily be understood by reference to Figure 3. The glove gauntlet 8 is usually constructed of a relatively flexible and bendable material, which, when in its normal expanded condition, as shown in Figure 1, will retain its shape. It may, however, be readily collapsed or folded upon itself, as shown in Figure 3, for convenient insertion through the

small end of the gauntlet shield 24, after which it may be expanded to its normal shape, within the shield 24, whereby its walls may fit snugly against the walls of the shield in such manner as to prevent accidental detachment of the shield 24 from the glove when the latter is in use or tossed about from place to place.

The shield 24 is preferably made of a relatively light, substantially nonflexible, fireproof material, such as the back shield 16, whereby it normally retains its shape, as shown in the drawings. The shield 24 may be made from a single blank of sheet material so cut that when folded into shape with its marginal ends overlapping, said overlapped edges may readily be secured together by suitable rivets 25, as indicated in Figures 2 and 3. The gauntlet shield 24 is so shaped that when fitted over the gauntlet 8 of the glove, its forward edge preferably extends slightly under the rear edge portion of the back shield 16, as best shown in Figure 1. By thus extending the back edge of the back shield 16 over the front portion of the gauntlet shield 24, sparks or bits of molten metal are not likely to enter between the back shield and back of the glove, as will be understood.

In Figure 7, I have shown a glove of slightly modified construction, wherein a leather strip 27 is substituted for the leather strip 14 shown in the previous figure. The strip 27 is secured to the side edge portion of the palm 28 of the glove by suitable rivets 29. Rivets 31 secure the back shield 26 to the leather strip 27, whereby when the shield 16 is in position over the back 2 of the glove, the leather strip 27 will cover or conceal the usual seam 12 which secures together the back and palm portions 2 and 28, as will readily be understood.

As hereinbefore stated, the glove is extremely simple and inexpensive to manufacture and readily lends itself for quantity manufacture. The fireproof shields 16 and 24 may be made of relatively thin fireproof fiber board which is light in weight, and is relatively stiff or nonflexible, whereby the composite glove when completed will be very light in weight. The back shield 16, however, has sufficient flexibility to allow the user to readily bend his fingers, as indicated in Figure 1, to permit picking up small objects and other articles, and also whereby a welding rod may readily be grasped.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only and that my invention is not limited thereto.

What I claim is:

1. In a welder's glove comprising the usual back, palm, and finger portions, seams securing together said back and palm portions along the sides of the glove, a strip of flexible material interposed between the back and palm portions along the forefinger side of the glove and secured therebetween by the seam securing together said portions, and a fireproof shield having one of its side edge portions secured to said flexible strip and overlying the back of the glove with its opposite edge suitably secured to the

opposite side of the glove, thereby to provide a protective covering for the back of the glove against sparks and bits of molten metal which may fly from the work during a welding operation.

2. In a welder's glove comprising the usual back, palm, and finger portions, seams securing together the back and palm portions along the sides of the glove, a strip of flexible material interposed between the marginal edges of the back and palm portions at each side of the glove and secured in position therebetween by said seams, said strips of flexible material extending to the tips of the fore and fourth fingers, and a substantially nonflexible fireproof shield having its opposite side edges secured to said flexible strips with its remaining portions free from the glove body to provide for free movement of the fingers.

3. In a welder's glove comprising the usual back, palm, and finger portions, seams securing together said back and palm portions along the sides of the glove, said seams extending to the tips of the fore and side fingers, a strip of leather interposed between the back and palm portions at each side of the glove and secured therebetween by said seams, a substantially non-flexible fireproof shield overlying the back of the glove and having its marginal side edges secured to the free edge portions of said leather strips, the forward central portion of said shield being free from the glove fingers and extending slightly

beyond the tips of the fingers, and the rear portion of said shield overlying the wrist and being free from the wrist portion of the glove.

4. In a welder's glove comprising the usual back, palm, and finger portions, seams securing together said back and palm portions along the sides of the glove, said seams extending to the tips of the fore and side fingers, a strip of leather interposed between the back and palm portions at each side of the glove and secured therebetween by said seams, a substantially non-flexible, thin, fireproof shield overlying the back of the glove and having its marginal side edges secured to the free edge portions of the leather strips, the forward central portion of said shield being free from the glove fingers and extending slightly beyond the tips of the fingers, and said shield having a lateral extension overlying a portion of the back of the glove to protect it against sparks and bits of molten metal.

ROBERT BAKKE.
